GOLF CLUB HANDLE

Filed Dec. 9, 1929

Sebastian Kramlik, INVENTOR
BY Victor J. Evans

ATTORNEY

WITNESS:

UNITED STATES PATENT OFFICE

SEBASTIAN KRAMLIK, OF KENILWORTH, NEW JERSEY

GOLF CLUB HANDLE

Application filed December 9, 1929. Serial No. 412,879.

This invention relates to golf clubs and has for an object the provision of a club handle which will accommodate a number of golf tees so that a player may have the tees 5 handy for use without carrying them in his or her pockets, the invention being especially useful for ladies.

Another object of the invention is the provision of a golf club handle for the above purpose, from which the tees may be readily and conveniently extracted, means being provided for yieldingly forcing the tees outward, and for retarding their outward movement, as well as for holding a closure cap in 15 position at the upper end of the club over the tees.

With the above and other objects in view, the invention further includes the following novel features and details of construction, 20 to be hereinafter more fully described, illustrated in the accompanying drawing and pointed out in the appended claims.

In the drawing:—

Figure 1 is a sectional view partly in elevation showing a portion of the shaft of a golf club with the invention applied.

Figure 2 is an enlarged fragmentary section of the outer end of the handle of the club.

Figure 3 is a section on the line 3—3 of Figure 2.

Referring to the drawing in detail wherein like characters of reference denote corresponding parts, the reference character 10 indicates a portion of the shaft of a golf club, and 11 the handle or grip. The club may be of any type desired, but it is preferred to incorporate the invention in the handle of a driver.

As illustrated in the drawing, the handle or grip of the club is provided with a socket 12, and positioned within the socket is a tubular member 13, which may be closed at its inner end as indicated at 14. The outer end 45 of this tubular member is provided with a

relatively thick annular flange 15 having recesses 16 disposed radially and the outer ends of these recesses are closed by a sleeve 17.

This sleeve is preferably provided with 50 an inwardly extending flange 18, so that a cup-shaped member is provided which receives the outer end of the tubular member 13.

Arranged within the sockets 16 are retaining elements or balls 19 which are forced 55 inward by means of springs 20, the ends of the sockets 16 however being so shaped as to prevent the balls from leaving the sockets. A ferrule 20' may surround the outer end of 60 the handle or grip 11.

The cylindrical member 13 is closed by a cap 21, and this cap carries a projection 22 which extends into the outer end of the tubular member and is provided with an annular groove 23 to receive the retaining elements 19. The cap 21 is thus yieldingly held 65 in position.

The tubular member which provides a socket within the handle of the club is adapted to contain a plurality of golf tees 70 24. The socket preferably accommodates eighteen tees for playing a round of golf. The tees are held within the socket by means of the cap 21 and the innermost tee rests upon a follower 25 which is forced outward by 75 means of a spring 26.

By reference to Figure 2 of the drawing it will be seen that when the cap 21 is removed, the spring 26 will force the tees outward so that the outermost tee may be grasped. The 80 retaining elements 19 resist this outward movement so that the tees must be manually removed. With the removal of a tee, the retaining elements 19 will engage the next adjacent tee so as to yieldingly hold this 85 and the remaining tees within the handle.

When the cap 21 is positioned, the tees will be forced inward so that the retaining elements 19 will engage the extension in the cap. When all of the tees are removed, the 90

retaining elements 19 will engage and prevent outward movement of the follower 25.

It is thus apparent that the retaining elements 19 perform three functions, namely; they yieldingly retain the cap in position to close the socket; they yieldingly resist outward movement of the tees, and they prevent outward movement of the follower 25.

The tees are preferably made of celluloid and are of such a size that eighteen tees, when nested within the handle will leave sufficient room for the compressed spring. The parts are so proportioned and of such weight as to compensate for the wood removed, so that a proper balance on the club will be maintained.

The invention is susceptible of various changes in its form, proportions and minor details of construction and the right is herein reserved to make such changes as properly fall within the scope of the appended claims.

Having described the invention what is claimed is:—

1. A holder for golf tees comprising a handle having a socket in its upper end to receive a plurality of golf tees, yieldable means to force the tees outward, a closure for the outer end of the socket, and means to retain the closure in position and to retard the outward movement of the tees when the closure is removed.

2. A holder for golf tees comprising a handle having a socket in its upper end to receive a plurality of golf tees, yieldable means to force the tees outward, a closure for the outer end of the socket, and yieldable elements extending into the socket adjacent the outer end of the latter to engage and yieldingly retain the closure in position and to retain the tees partially within the socket when the closure is removed.

3. A holder for golf tees comprising a handle having a chamber opening outwardly through the end thereof, a tubular member positioned in the chamber and having the inner end thereof closed and its outer end enlarged and positioned outwardly of the chamber and having oppositely disposed sockets, spring pressed balls in said sockets to frictionally engage the outermost tee of a plurality of nested tees located in the tubular member, a spring pressed follower for urging the tees in a direction outwardly of the tubular member and which are prevented from moving entirely outwardly of said tubular member by said balls, a cap to engage the open end of the tubular member, and a plug on said cap and extending into the tubular member and having a groove to receive the balls and thereby position the tees fully within the tubular member.

4. A holder for golf tees comprising a socketed member to receive a plurality of nested tees, a spring pressed follower engaging said tees to urge the latter outwardly

of said socketed member, a closure for said socketed member and having a grooved portion, and spring pressed elements carried by the member and engaging the grooved portion of the closure and adapted to engage the outermost tee when the closure is removed to prevent the tees from moving entirely out of the socketed member.

In testimony whereof I affix my signature.

SEBASTIAN KRAMLIK.
